UNITED STATES PATENT OFFICE.

ROBERT M. EASLEY AND FRANK L. EASLEY, OF KENTON, OHIO.

DESIGN FOR A CINDER-GUARD FOR RAILWAY-CAR WINDOWS.

49,882.

Specification for Design.

Patented Nov. 14, 1916.

Application filed October 30, 1915. Serial No. 58,918. Term of patent 14 years.

all whom it may concern:

Be it known that we, ROBERT M. EASLEY and FRANK L. EASLEY, citizens of the United States, residing at Kenton, in the county of Hardin and State of Ohio, have invented a new, original, and ornamental Design for Cinder-Guards for Railway-Car Windows, of which the following is a specification, reference being had to the accompanying drawing, forming part thereof.

Figure 1 is a perspective view of the cin-

der guard, showing our new design. Fig. 2 is an end elevation of the cinder guard, showing our new design.

We claim:

The ornamental design for a cinder guard for railway car windows, as shown.

ROBERT M. EASLEY.
FRANK L. EASLEY.
